INVENTOR

BY *Victor J. Evans*

ATTORNEY

WITNESS:

R. E. Evans

UNITED STATES PATENT OFFICE.

ORUM T. BRIGGS, OF INDIANA, PENNSYLVANIA.

PACKAGE CARD.

Application filed August 27, 1924. Serial No. 734,502.

This invention relates to an address card, the general object of the invention being to provide a card which is adapted to be tried or otherwise fastened to a package such as 5 a parcel post package and which is designed to contain the name of the sender, the name of the person to whom the package is sent and the stamp or stamps.

Another object of the invention is to provide the card with a space for the name of 10 the shipper so that it can be used for returning the package or another package.

A further object of the invention is to provide the card with an extension which 15 when folded upon the major part of the card and the card fastened to a package, will form a pocket for containing envelopes, cards or the like.

This invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the several views, and in which:—

Figure 1 is a view of a package showing the invention in use.

Figure 2 is a view of the device itself.

As shown in these views the device comprises a blank which is formed of the major part 1 and the minor part 2, the parts being separated from each other by the scored or weakened line 3 which forms a hinge for permitting the part 2 to be folded over upon the part 1. The outer edges of the parts 1 and 2 are each provided with an eyelet 4, the eyelets registering with each other when the parts are folded one upon the other so that a string 5 can be passed through the two eyelets when the device is placed on a package A to hold the two parts together. Thus a pocket is formed by the two parts in which can be placed envelopes, cards and

the like. The part 1 is provided with a pair of eyelets 6 at each end for receiving portions of the string as shown in Figure 1, so that the device is attached to the package by the string which is placed around the package to hold the cover thereon. The part 1 on each face contains the space 7 for the name of the person to whom the package is to be sent, a space 8 for the name of the person sending the package and a space 9 for the stamp. Thus one face of the part 1 can be used by the shipper for instance, and then the other face can be used by the customer in returning the article or another article to the shipper.

From the foregoing it will be seen that I have provided a simple device which can be used as a shipping card and which forms a pocket for containing cards, envelopes or the like and which is securely fastened to the package by the string which ties up the package.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A shipping card comprising a blank 80 formed of a major and a minor part, the minor part having its ends terminating short of the major part, the point of junction between the two parts being scored so that one part can be folded over onto the other 85 part to form a pocket, the outer marginal edges of each part having an eyelet, which eyelets are adapted to align when the parts are folded and the major parts having spaced eyelets at each end with all of said eyelets 90 adapted to receive a tieing string therethrough for retaining the pocket in a closed position as and for the purpose set forth.

In testimony whereof I affix my signature.

ORUM T. BRIGGS.
